UNITED STATES PATENT OFFICE.

FRITZ LUTHER, OF DESSAU, GERMANY, ASSIGNOR TO G. POLYSIUS, OF DESSAU, GERMANY, A FIRM OF GERMANY.

DRYING APPARATUS FOR ROTARY KILNS.

Application filed May 26, 1927. Serial No. 184,510.

This invention relates to rotary kilns or rotary driers and more particularly to means for rapidly evaporating water from materials to be treated in the kiln or drier, such as for instance as slurry, or the like used in manufacturing cement.

In carrying out my invention, I provide curved baffles at the inlet part of the rotary drum, said baffles each having one end secured to the drum wall and the other projecting into the interior of the drum.

By means of my improved construction, the time required for the driving off of the water is materially reduced and therefore it is possible to materially reduce the total length of the drum. This reduction in time as well as in the length of the drum causes a saving in the cost of the apparatus and results in an increase in efficiency.

20 In the accompanying drawings, there is illustrated one embodiment of my invention.

In these drawings:

Fig. 1 is a central longitudinal section of the inlet end portion of a rotary drum; and

25 Fig. 2 is a transverse section on the line 2—2 of Fig. 1.

In the construction illustrated, the inlet end portion of the rotary drum *a* is provided with a series of longitudinally extending 30 baffles *b* which are preferably curved. Each baffle has one end secured to the peripheral wall of the drum in any suitable manner, while the other end extends to the interior of the drum.

35 The baffles are preferably of such material that their inner edges may vibrate or bend due to the weight or action of the material which is elevated by the baffles during the rotation of the drum. The baffles are so 40 curved that during the rotation of the drum in the direction indicated by the arrow in Fig. 2, the material is lifted by the several baffles in succession and drops off the free edge on to the next succeeding baffle. This 45 impact of the material causes the vibration

or oscillation of the baffles and the agitation of the material. It also causes air currents between the baffles which aid in bringing the air or heating gases into the most intimate contact with the material to effect the rapid 50 drying thereof.

By proper regulation the major portion of the water is eliminated from the material by the time it reaches the end of the baffles in its travel lengthwise of the drum. The 55 elimination of water is aided also by the fact that after the material drops off the edge of each baffle, the surface of the baffle remains wet and this moisture is removed while the baffle is in the upper portion of 60 the drum.

Having thus described my invention, what I claim as new and desire to secure by Letters Patent is:

1. A rotary drum for the heat treatment 65 of material, having at the inlet portion thereof comparatively wide longitudinally curved baffle plates extending lengthwise of the drum, one edge of each baffle being secured to the peripheral wall and the other 70 edges being free, the said baffles being flexible whereby as material falls from the longitudinal free edge thereof, the said edge may oscillate and scatter the falling material. 75

2. A rotary drum for the heat treatment of material, having at the inlet portion thereof comparatively wide curved baffle plates extending lengthwise of the drum and projecting to a considerable distance into 80 the drum, one edge of each baffle being secured at the peripheral wall, the baffle being flexible whereby the opposite longitudinal edge may swing free and the material in falling from said free edge may cause said 85 edge to oscillate and the material to be scattered.

Signed at Leipzig, Saxony, Germany, this twelfth day of May, 1927.

FRITZ LUTHER.
